UNITED STATES PATENT OFFICE.

ADOLF PILGER, OF MARSHWOOD, PENNSYLVANIA.

MATCH-BOX.

1,248,908.

Specification of Letters Patent. Patented Dec. 4, 1917.

Application filed October 16, 1916. Serial No. 125,831.

To all whom it may concern:

Be it known that I, ADOLF PILGER, a subject of the Emperor of Germany, and a resident of Marshwood, in the county of 5 Lackawanna and State of Pennsylvania, have invented certain new and useful Improvements in Match-Boxes, of which the following is a specification.

This invention relates to improvements in 10 combined match dispensers and cigar clippers and has as its principal object the provision of a receptacle in which matches may be contained in bulk and provided with arrangements for the delivery of one or more, 15 as may be desired, the delivery means being combined with other means adapted to clip the end of a cigar butt.

A further object is to provide with such apparatus a receptacle in which cigars or 20 the like may be stored and a still further object is to provide such devices in attractive forms suitable for display on counters of cigar stores, or other like public places.

These and similar objects are attained by 25 the novel construction and combination of parts hereafter described and shown in the accompanying drawings, forming a material part of the specification and in which:—

Figure 1 is a top plan view showing the 30 apparatus in its preferred form.

Fig. 2 is a front side elevation of the same, parts being broken away in order to show the interior.

Fig. 3 is a transverse sectional view, taken 35 on line 3—3 of Fig. 1.

Fig. 4 is a similar transverse sectional view, taken on line 4—4 of Fig. 5.

Fig. 5 is a vertical sectional view taken 40 on line 5—5 of Fig. 3.

Fig. 6 is a similar sectional view taken on line 6—6 of Fig. 3, and

Fig. 7 is a perspective view of the clipping device, looking from the lower side.

The preferred form of the device includes 45 a rectangular structure having longitudinal side elements 10 and 11, connected by a base plate 12 and end elements 13 and 14. A partition plate 16 extends over the receptacle thus forming a hollow rectangular box. A 50 partition plate 16 extends transversely from top to bottom, parallel with the end elements 13 and 14 forming a compartment 18 in the lower portion of which is a removable drawer 19, the same being directly under a passage 21, formed between the side plate 11 and another vertical partition 20, the

drawer being adapted to receive and contain the clippings from the end of a cigar, entered through the conical guide opening 22, formed through the cover of the box, 60 adjacent to one end thereof and along one of its side edges.

Near the opposite end is a push button 25, the same being guided as it extends downwardly through the cover and has attached 65 at its lower end, a stem or spindle 26, passing through fixed guides 27, attached rigidly to the side plate 11 and terminating below the lower guide in an enlarged beveled head 28, as can best be seen in Fig. 3. 70

A coiled spring 29 exerts pressure between the lower guide 27 and a collar 30 rigidly engaged upon the spindle, tending to hold the push button in a raised position, which is limited by the location of the collar, 75 adapted to make contact with the upper guide when in a normal raised condition.

Also attached to the spindle 26, is the end 32 of a bell-crank lever, fulcrumed at 33 and containing a slot 34 through which the pin 80 35, set in the spindle, operates, thereby conveying motion to the lever, the other end 37 of which is engaged with the bent end 38 of a link 39 guided in bearings 40 and passing through the partition plate 16, where its 85 outer end is pivotally connected with a shear or knife blade 42, pivoted at 43 to the inwardly projected end of the cigar receiver 22. Thus when the spring 29 is in a normal position the knife is removed from 90 the opening of the interior of the clipper so as to permit a cigar to enter. At the same time the bar 45 having guides 46, is pressed toward the head 28 by means of the coiled spring 48, surrounding a stem 49 95

slidable in an elongated bearing 50 and having at its outer end a collar 51 engaged with which is a pressure plate 52 made of some elastic materials as rubber, the same projecting through the wall 53 into the match compartment 54. In this compartment the matches 55 are disposed upon angular flooring 56 terminating in a down turned end 57, separated from continuations of the partition 53 by such a distance as to permit of a single row of matches to enter therebetween, forming an elongated flattened tube. 100

The lower end of this tube is provided with a cover plate 58 hinged at 60 and having a lug 61 extending vertically above, 110 against which the detent 62 is adapted to

make contact, when the knob 25 is depressed.

This contact allows matches to drop down upon the inclined plate 65, set in the lower 5 part of the receptacle where they will roll, by gravity, toward the lower front edge and be received upon a corrugated striking surface 66 and having an angular margin 67 to prevent the matches from rolling entirely 10 out of the receptacle.

The upper part of the container is arranged with chambers 70 and 72 adapted to contain cigars and cigarettes, as best shown in Fig. 4. From the foregoing description 15 it will be obvious that upon pressure of the knob 25, one or more of the matches will be liberated and brought into position where they are readily accessible, coincidentally with clipping the end of the cigar.

Having thus described my invention, what 20 I claim as new and desire to secure by Letters Patent is:—

In a device of the character described the

combination with a receptacle for containing matches, a sliding element mounted adjacent said receptacle, said sliding element having a wedge shaped member at one end thereof and a sleeve at its opposite end, a spring pressed element carried by said sleeve and adapted to extend into the match receptacle for permitting the discharge of only a predetermined quantity of matches from the match receptacle, a hinged closure for said receptacle for controlling the discharge of the matches therefrom, a spring element 35 carried by the sleeve for actuating said closure, a spindle mounted adjacent the receptacle, spring controlling means therefor, and a wedge shaped member mounted upon one edge thereof for engaging the wedge shaped member upon the sleeve for operating the latter.

Signed at Marshwood, in the county of Lackawanna, and State of Pennsylvania, this 9th day of October, 1916.

ADOLF PILGER.
